UNITED STATES PATENT OFFICE

2,204,700

TOY OR DISPLAY DEVICE

Hanson Robinson, Wayne, Pa.

Application October 7, 1937, Serial No. 167,742

2 Claims. (Cl. 272—27)

The object of the invention is to provide an improved toy or display device, of a type of such size as to adapt it to being pinned or otherwise detachably secured to a person's coat, vest, or other article of clothing.

Another and more particular object is to provide a toy of such character as to engender group or club enthusiasm, especially among young boys and girls, and towards that end one of its principal features is the provision of a normally hidden flag or in fact any other desired emblem, together with suitable manually actuatable means, whereby actuation of said means operates to eject such emblem into prominent visibility, and from which exposed position it is returned automatically to its hidden and protected position, upon the release of said actuating means.

A further object is to provide such a device, the combination of a casing for the emblem above mentioned, which casing has a properly positioned aperture, towards which leads a tube from a compressible reservoir, preferably in the form of a suitable rubber bulb or similarly collapsible member, which may be carried out of view, as for instance within the article of clothing, by which the device as a whole is supported.

A further and more detailed object is the provision of an oscillatable support for an emblem, such as a flag or the like, said support preferably comprising means to maintain the emblem in constantly upright position, and its path of movement substantially rectilinear, as said emblem moves from a hidden to an exposed position, and vice versa.

With the objects thus briefly stated, the invention comprises further details of construction and operation, which are hereinafter fully brought out in the following description, when read in conjunction with the accompanying drawing, in which Fig. 1 is a front elevation of a device comprising one embodiment of the invention; Fig. 2 is a vertical, substantially central section of the same; Fig. 3 is a section on the line 3—3 of Fig. 2; Fig. 4 is an elevational view of a fragmentary portion of the rear of said device; and Fig. 5 is a fragmentary detail view.

Referring to the drawing, a hollow disc-like casing support is provided, the same comprising a planar front wall 1, an initially separate rear wall 2 and a peripherally extending side wall 3, having a relatively wide aperture 4 in its normally upper portion, in addition to a relatively restricted aperture 5 in its normally lower portion, said rear wall being fixedly secured to the remaining portions of said casing support by any

suitable means, such for instance, as the marginal radially inwardly directed flange 6.

The outer surface of the front wall 1 may be shaped and/or lithographed, or otherwise embellished so as to embody any desired type or form of indicia, but for purposes of illustration is shown in the present instance as comprising a centrally positioned, embossed shield 7 upon the laterally opposite sides of which are embossed stars 8, or the like, while said shield is in turn more highly embossed at its center to represent a cannon or mortar 9 between parallel embossed stripes 10, representing the wheel supports for such cannon, or otherwise a mere further ornamentation of said shield. Additionally, said shield 15 may carry either or both embossed and lithographed words or phrases, as illustrated by the words "Salute! Our Club," which appear upon Fig. 1 of the drawing, but it is to be understood that the particular shape, arrangement and coloring of such embossing and ornamentation is merely representative of the infinite number and ways in which the ornamentation or embellishment of the device may be carried out.

It will be noted that closely adjacent to the upper end of the cannon 9, the front wall 1 is provided with a laterally elongated yet restricted emission orifice 11, through which projects the discharge end of a slender rubber tube 12, securely affixed to the rear or inner surface of said front wall by any suitable means, such as is hereafter described, whence said tube extends downwardly through the aperture 5 in the peripheral side wall 3, beneath which said tube merges into a freely flexible portion 13 and is adapted to be connected at its opposite end 14 with a collapsible rubber or similar reservoir 15, which the owner of the device may carry positioned within his coat, vest, shirt, or other article of clothing. The reservoir 15 may embody any desired shape, as for instance, a spherical, elliptical bulb, or the like, but in this case is shown as preferably comprising a vertically elongated, hollow member initially open at its upper end, and provided with radially outwardly directed flanges 16, which are surrounded and gripped by reversely directed flanges 17, carried by a closure plate 18 having a filling port 19 normally closed by a removable stopper 20 and with a discharge port 21 surrounded by a flange 22, by means of which the outer free end 14 of the tube is connected to the plate 18.

Within said casing and extending between the oppositely positioned front and rear walls thereof are a pair of pivot pins 23, to which are respectively connected one end of each of a pair of 55

substantially parallel links 24, the opposite ends of which links are likewise pivotally connected at 25 to a lower staff-like extension 26 of an emblem 27, which in this instance is shaped and colored to represent the flag of the club, preferably carrying an outwardly directed extension 28, to represent the ball that is frequently provided upon the outer end of a flag staff.

In addition to the force of gravity, said emblem-carrying member is normally maintained in its lowermost withdrawn position by means of a suitable spring 29, connected to and extending between one of the said links 24 and a lower portion of the side wall 3, as for instance at 30. In order to effect the elevation of the member 27 against the tension of said spring, the depending extension 26 is provided with a lug 31, to which is connected a flexible actuating member 32, which thence extends upwardly and reversely downwardly through a semi-tubular guide 33, secured by lugs 34 to the rear face of the forward wall 1, laterally with respect to and partially surrounding the upper terminal portion 12 of the tube and the emission aperture 11, said tube being securely positioned adjacent to said aperture by the encircling arms of an inverted T-shaped extension 33a of the central portion of the guide 33.

From the opposite or depending end of said guide, the flexible actuating member 32 extends downwardly through and freely from an aperture 35 in the side wall 3, and if desired may carry upon its free end a ball or button 36, to facilitate manual actuating of said oscillatable member. The rear wall 2 of the casing may also be provided with any suitable form of pin or attaching means 37, attached to said rear wall by pivot supporting ears 38, and its free pointed end portion being normally in engagement with a suitable retainer 39, said ears and said retainer for the sake of economy being preferably punched outwardly from said rear wall.

From this general construction, it will be apparent that attention may be drawn to the device by the wearer pulling downwardly upon the flexible member, thereby shifting the emblem-carrying member upwardly into clearly visible position beyond the lateral limits of said casing, as indicated by the dot-and-dash lines in Fig. 1. Thereupon, as the one attracted by the sudden appearance of said member approaches the wearer of the device, in order to

more carefully examine the same, the wearer can so press upon the collapsible reservoir preferably hidden within his clothing, that the fluid with which said reservoir is filled will be as suddenly ejected from the restricted emission aperture 5 towards the one examining the device.

Finally, it is to be understood that various changes may be made in the structural details herein described, without departing from the spirit of the invention as defined by the appended 10 claims, it being understood among other details that the term fluid, as used herein, is intended to include any desired liquid, gas, or powdered substance capable of being ejected from the device.

Having thus described my invention, what I claim as new and desire to protect by Letters Patent of the United States is:

1. A toy or display device, comprising a hollow disc-like casing having an aperture in one portion of its periphery, an oscillatable member normally carried by and within said casing and adapted to be extended through said aperture, parallel links pivotally connecting said member to said casing, flexible means connected to said member to manually raise said member outwardly from within said casing, means to automatically return said member to its initial position upon being released by said last-mentioned means, and an inverted hollow U-shaped guide 30 for reversing the direction of said flexible means, which guide being in close relation with a wall of said casing, forms a tubular channel.

2. A toy or display device, comprising a hollow disc-like casing having an aperture in one portion of its periphery, an oscillatable member normally carried by and within said casing and adapted to be extended through said aperture, interengageable means slidably connecting said casing and said member so as to restrain oscillation of said member to a predetermined path, 40 flexible means connected to said member to manually raise said member outwardly from within said casing, means to automatically return said member to its initial position upon being released by said last-mentioned means, and an inverted hollow U-shaped guide for reversing the direction of said flexible means, which guide being in close relation with a wall of said casing, forms a tubular channel.

50

HANSON ROBINSON.
